VACUUM CLEANER

Charles L. Brown, Jr., Stamford, Conn., assignor
to Electrolux Corporation, Dover, Del., a cor-
poration of Delaware

Application December 21, 1937, Serial No. 181,018

8 Claims. (Cl. 230—47)

My invention relates to vacuum cleaners and more particularly to vacuum cleaners of the type having a unit supported on the floor and connected to a cleaning tool by a flexible hose or conduit.

In vacuum cleaners of this type an opening is provided at the suction end of the unit in which the hose may be connected for normal use as a suction cleaner. Exhaust openings are provided at the other end of the unit with means for directing the air upwardly as it leaves the openings so it will not disturb any dust or dirt on the floor or surface on which the unit is supported. At times the unit is used as a blower by connecting the hose in one of the exhaust openings. Heretofore a sliding louver has been provided in one of the exhaust openings normally serving to direct the air leaving the opening upwardly but movable to permit the insertion of the hose. Also the sliding louver has been arranged to close the other exhaust openings upon the insertion of the hose to direct the air from the unit into the hose. The advantage of providing exhaust openings in addition to the one that may be used for connecting the hose for blower action lies in the fact that the larger the area of the exhaust openings the lower the back pressure will be when the unit is used as a suction cleaner.

In accordance with my invention, an improved louver assembly is provided for the exhaust end of a vacuum cleaner unit with fixed vanes and a sliding louver of simplified construction.

What I consider to be novel in my invention may be better understood by reference to the following specification and appended claims when considered in connection with the accompanying drawings, in which

Fig. 1 is a side view partially in section of a vacuum cleaner unit embodying my improved louver assembly;

Fig. 2 is a rear view of the unit shown in Fig. 1;

Fig. 3 is an enlarged cross-sectional view of the louver assembly taken along the lines 3—3 of Fig. 2;

Fig. 4 is a detailed view partly in section taken on lines 4—4 of Fig. 3;

Fig. 5 is an enlarged sectional view similar to Fig. 3 except that the hose is shown connected in one of the exhaust openings;

Fig. 6 is a detailed sectional view taken along the lines 6—6 of Fig. 5.

Referring particularly to Fig. 1, numeral 10 designates generally a vacuum cleaner having

5 a casing 11 of substantially cylindrical cross section which is mounted on sleighs 12. One end of casing 11 is closed by a removable cover 13 with a suction aperture 14 in which a flexible 10 hose 15 may be connected. At the other end of hose 15 a cleaning tool 16 is connected by means of a substantially rigid hollow tube 17.

A dust separating member 18 is secured in casing 11 by means of a flanged ring 19 which is clamped between the casing 11 and the cover 13. The dust separating member 18 is in the form of a bag made of a fine texture cloth or other material which will permit the passage of air therethrough but will separate out any dust particles entering with the air. When it is desired to clean the dust separating member 18 of the dust collected in it, the cover 13 is removed and the dust separating member taken out of the casing 11 and emptied. A motor-fan unit including an electric motor 20 and a multi-stage centrifugal fan 21 is mounted in the casing 11.

In normal operation air enters the cleaning tool 16, passes through the hose 15, through the aperture 14, and into the casing 11. During the 15 passage of the air through the dust separating member 18 any entrained dirt or dust is separated therefrom. The air then continues through the fan 21 and motor 20 and out through the exhaust openings provided in a louver assembly 22.

20 Louver assembly 22 is removably secured by two knurled headed screws 23 in a rear end housing 24 carried by casing 11. Two exhaust openings 25 are located in the top of the louver assembly 22 and are arranged symmetrically on opposite sides of the vertical center line. A circular exhaust opening 26 is located in louver assembly 22 below the two exhaust openings 25. In circular exhaust opening 26 a sliding louver 27 is mounted with inclined vanes 28. Sliding louver 27 is normally held flush with the surface of louver assembly 22 in engagement with an inturned flange 29 of a stop ring 30 located in exhaust opening 26 by means of a substantially conical spiral spring 31. In this position the inclined vanes 28 direct the air passing through exhaust opening 26 upwardly away from the surface on which the vacuum cleaner unit 10 is supported so the air will not disturb any dust located on this surface. The exhaust openings 25 are provided with inclined vanes 32 for the same purpose as vanes 28.

25 The two exhaust openings 25 and the exhaust opening 26 together provide a relatively large area through which the air may be exhausted when the cleaner unit 10 is used as a suction

cleaner. In this way the back pressure at the exhaust end of the cleaner unit is kept low. When it is desired to use the cleaner unit 10 as a blower the hose 15 is connected to the exhaust end of the cleaner unit. The hose 15 is inserted in the circular exhaust opening 26 moving the sliding louver 27 to the left as shown in Fig. 5 against the bias of spring 31. A plurality of latches 33 carried by hose 15 secure it in opening 26 by engagement with the inturned flange 29 of stop ring 30.

When the hose 15 is connected in exhaust opening 26 the inherent resistance of the hose would tend to reduce the amount of air flowing through opening 26 and divert the major portion of the air through the exhaust openings 25. This tendency is overcome by utilizing the sliding louver 27 to close the exhaust openings 25 upon the insertion of the hose 15. A louver housing 34 with a port 35 is secured to the louver assembly by means of screws 36. Port 35 is provided with a curved lip 37. Two flat plates 38 and an arched plate or partition 39 divide housing 34 into two chambers. Top chamber 40 communicates with the two exhaust openings 25 and bottom chamber 41 communicates with the exhaust opening 26. Port 35 communicates directly with the bottom chamber 41 and through a passage 42 with the top chamber 40.

Sliding louver 27 has two out-turned ears 43 which ride on tracks formed by two Z-shaped guides 44 secured to plate 38. The small end of spring 31 which moves sliding louver 27 to the right and opposes movement to the left, as shown, is seated in a central seat 45 provided in a cross bar 46 extending across port 35. When the sliding louver 27 is moved to the left by insertion of hose 15 in opening 26 a skirt 47 carried by sliding louver 27 closes the passage 42 to the top chamber 40. With the sliding louver 27 in the position indicated in Fig. 5, the skirt 47 extends from the lip 37 of port 35 to the partition 39. To insure an air-tight seal when passage 42 is closed a compressible ring gasket 48 of soft rubber or other flexible material is located around the lip 37 of port 35. In this manner the passage 42 communicating with top chamber 40 and exhaust openings 25 is closed when hose 15 is secured in opening 26 thereby directing the air into the hose 15 and closing openings 25.

The partition 39 in addition to its function as a separating wall between chambers 40 and 41 serves as a guide for the sliding louver 27. The skirt 47 engages the partition 39 throughout its movement and so it cannot be accidentally inclined in its movement which might cause it to bind or stick.

In normal operation the hose 15 is connected in the aperture 14 of the front end cover 13. Dirt-laden air is picked up by the cleaning tool 16 and passes into the cleaning unit 10 through hose 15. The dirt entrained in the air is separated therefrom in the passage of the air through the dust separating member 18. The air then passes through the multi-stage centrifugal fan 21 and from the fan through or around the motor 20. The air then enters the louver assembly 22 through the port 35. A portion of the air passes directly out through the exhaust opening 26. The sliding louver 27 is held flush with the surface of louver assembly 22 by means of spiral spring 31. The vanes 28 carried by the sliding louver 22 direct the air passing out through exhaust opening 26 in an upward direction. Another portion of the air en-

tering port 35 passes upwardly through the passage 42 into the chamber 40. The air entering chamber 40 passes out through the exhaust openings 25 and is directed upwardly by the vanes 32.

When it is desired to utilize the blower action of the vacuum cleaner unit 10, the hose is disconnected from the aperture 14 and connected in the exhaust opening 26. The latches 33 secured to the end of hose 15 engage the inturned flange 29 provided on stop ring 30. When the hose 15 is inserted in the opening 26, sliding louver 27 is moved to the left, as shown in Fig. 5, against the bias of spring 31. When the hose 15 has been secured in the opening 26, sliding louver 27 is in the position indicated in Fig. 5 with its skirt 47 closing the passage 42 between the lip 37 of port 35 and the partition 39. Air entering the aperture 14 of the front end cover 13 passes through the casing 11 and enters the port 35. The air entering port 35 passes out through the hose 15. For disconnecting the hose 15 from the exhaust opening 26 fingers 49 are provided for releasing latches 33. When the hose 15 is removed from the exhaust opening 26, sliding louver 27 is returned to its position flush with the outer surface of louver assembly 22 by means of spring 31. The cleaner unit 10 is then in condition for use as a suction cleaner upon connection of the hose 15 in the aperture 14.

By the arrangement of the louver housing 34 divided into two chambers by the plate 38 and partition 39 and the utilization of the skirt 47 of sliding louver 27 to close the passage 42 to the top chamber 40 upon the insertion of hose 15 in the opening 26 a simple and efficient construction is provided to maintain a low back pressure for normal use of the cleaner unit as a suction cleaner and to direct the air into the hose for the use of the blower action of the cleaner unit. Among the other features of this construction of importance are the tracks formed by the guides 44 and plates 38 together with the partition 39 which carry and guide the sliding louver 27 upon its movement from one position to another.

What I claim is:

1. In a vacuum cleaner, a casing, means for producing a flow of air through said casing, a louver assembly secured to said casing having a plurality of exhaust openings, a housing located in said casing secured to said louver assembly and having a port, two flat plates and an arcuate partition secured to said housing forming within said housing a first chamber communicating with one of said exhaust openings and said port and a second chamber communicating with the other of said exhaust openings and through a passage with said port, a sliding louver mounted in said one of said exhaust openings, a spring biasing said sliding louver to a position flush with the surface of said louver assembly, means upon insertion of a hose in said one of said exhaust openings displacing said sliding louver against the bias of said spring, and a skirt carried by said sliding louver closing the passage from said port to said second chamber upon the insertion of said hose in said one of said exhaust openings.

2. In a vacuum cleaner, a casing, means for producing a flow of air through said casing, a louver assembly secured to said casing having an exhaust opening, a housing within said casing enclosing said exhaust opening secured to said louver assembly, a plate secured to said housing,

a guide connected to said plate forming a track, and a sliding louver having an ear riding on said track.

3. In a vacuum cleaner, a casing, means for producing a flow of air through said casing, a louver assembly secured to said casing having an exhaust opening, a housing within said casing enclosing said exhaust opening secured to said louver assembly and having a port, a partition dividing said housing into two chambers, guides carried by said partition, and a sliding louver mounted in said exhaust opening having ears engaging said guides.

4. In a vacuum cleaner, a casing, means for producing a flow of air through said casing, a louver assembly secured to said casing having a plurality of exhaust openings, a housing within said casing secured to said louver assembly enclosing said exhaust openings and having a port, a partition dividing said housing into a first chamber communicating with one of said exhaust openings and said port and a second chamber communicating with the other of said exhaust openings and through a passage with said port, tracks secured to said partition, a sliding louver mounted in said one of said exhaust openings riding on said tracks guided by said partition, a spring biasing said sliding louver to a position flush with the surface of said louver assembly, means upon insertion of a hose in said one of said exhaust openings displacing said sliding louver against the bias of said spring, and a skirt carried by said sliding louver closing the passage from said port to said second chamber upon the insertion of said hose in said one of said exhaust openings.

5. In a vacuum cleaner, a casing having a suction opening at one end and a plurality of exhaust openings in the other end, means for producing a flow of air through said casing, a hollow member within said casing having a port at one end and enclosing said exhaust openings, tracks secured to said hollow member, a member mounted in one of said exhaust openings on said tracks having exhaust louvers and an extension closing a passage communicating with the other of said exhaust openings when a hose is connected in said one of said exhaust openings.

6. In a vacuum cleaner, a casing, means to produce a flow of air through said casing, a louver assembly secured to said casing having a plurality of exhaust openings, a hollow member

5 within said casing secured to said louver assembly and having a port, a partition secured to said hollow member forming with said hollow member a top chamber communicating with an exhaust opening and through a passage with said port, tracks secured to said hollow member, a sliding louver located in another of said exhaust openings riding on said tracks, a skirt of said sliding member adapted to close the passage between said port and said first-named exhaust opening upon the connection of a conduit in said last-named exhaust opening, whereby air flowing through said casing passes out through said conduit.

7. In a vacuum cleaner, a casing, means for producing a flow of air through said casing, a removable cover secured to one end of said casing having a suction aperture, a louver assembly secured to the other end of said casing having a plurality of exhaust openings, a sliding louver mounted in one of the exhaust openings and having inclined vanes to direct air passing therethrough upwardly, inclined vanes located in the other exhaust openings, a hollow housing secured to said louver assembly having a port, a partition of semi-cylindrical shape secured to said housing and forming a passage between said port and said exhaust openings, and an extension from said sliding member closing the passage to the other exhaust openings upon the insertion of a hose in said one exhaust opening whereby air passing through the casing enters the hose.

8. In a vacuum cleaner, a casing having a suction opening at one end, means for producing a flow of air through said casing, a louver assembly secured to the end of said casing remote from said suction opening having a plurality of exhaust openings, a hollow housing having a port secured to said louver assembly within said casing, a partition secured to said housing between one of said exhaust openings and the other of said exhaust openings and forming a passage between said port and the other of said exhaust openings, tracks secured to said housing, a sliding louver mounted on said tracks, a spring biasing said sliding louver to a position flush with the surface of said louver assembly, and an extension of said sliding louver closing the passage communicating with the other of said exhaust openings upon movement of said sliding louver against the bias of said spring.

CHARLES L. BROWN, JR.
